UNITED STATES PATENT OFFICE.

JOHN R. MARDICK, OF NEW YORK, AND FREDERICK MARK BECKET, OF NIAGARA FALLS, NEW YORK, ASSIGNEES TO ELECTRO METALLURGICAL COMPANY, OF NIAGARA FALLS, NEW YORK, A CORPORATION OF WEST VIRGINIA.

EXPLOSIVE.

1,335,789.

Specification of Letters Patent. Patented Apr. 6, 1920.

No Drawing.

Application filed June 19, 1918. Serial No. 240,793.

To all whom it may concern:

Be it known that we, (1) JOHN R. MARDICK and (2) FREDERICK M. BECKET, (1) a citizen of the United States and (2) a subject of the King of Great Britain, residing at (1) New York, (2) Niagara Falls, in the counties of (1) New York, (2) Niagara, and State of New York, have invented new and useful Improvements in Explosives, of which the following is a specification.

This invention relates to certain novel explosive compositions suitable for blasting and other commercial purposes, and containing as essential components one or more normally solid nitro-aromatic bodies having at least three nitro-groups, of which tri-nitro-toluol (T. N. T.) and picric acid are types, associated with an oxidizing agent or agents and a magnesium-silicon alloy.

A general formula for an explosive composition embodying our invention is as follows:

Nitro aromatic compound

or compounds ----- 15-30% by weight
25 Magnesium-silicon alloy ----- 5-15% by weight
Oxidizer ----- 50-75% by weight
Combustible ----- 0-5% by weight
Plasticizing ingredient ----- 1-5% by weight
Anti-acid ----- 0-1% by weight

An illustrative formula for a commercial (blasting) explosive of the plastic type, capable of being tamped into place, is as follows:

35 Picric acid or T. N. T. ----- 17 %
Magnesium-silicon alloy ----- 10 %
Ammonium nitrate ----- 35 %
Sodium nitrate ----- 31.5 %
Dinitrotoluol ----- 3 %
40 Wood flour ----- 3 %
Calcium carbonate ----- 0.5 %

Each of the essential components of the explosive performs a function in the mixture, and the proportions of the components will be varied in practice as may be necessary to the proper performance of this function, having in view the specific purpose for which the explosive is intended.

50 The nitro-aromatic bodies are normally solid but readily fusible, and are therefore easily compounded with the other ingredients, yielding cohesive plastic compositions which are readily tamped into conformity

to the bore. Instead of T. N. T. or picric acid I may use other nitro-aromatic bodies having similar desirable qualities, as for example tri- and tetra-nitro-naphthalene, and the tri-nitro cresols.

The oxidizer is in sufficient proportion to convert any carbon monoxide into carbon dioxide and serves in general to oxidize all poisonous or objectionable gases or compounds, rendering the products of explosion innocuous. It is also used in sufficient excess to effect oxidation of the paraffined paper wrapper usually employed. The wood flour or other combustible will unite with any otherwise unconsumed excess of the oxidizing component. The use of the anti-acid body is precautionary, guarding against development from any cause of an acid condition in the mixture.

In case a hygroscopic salt such as ammonium nitrate is used I prefer to introduce into the mixture small proportions, say four per cent. or less, of a liquid capable of coating the salt and thereby protecting it from atmospheric moisture. For this purpose I may use vaseline, oils, etc.; but I prefer liquid nitro bodies such for example as the liquid nitro xylenes, o-dinitro benzene, di-nitro toluene or the like. These liquid nitro bodies act as deadening agents, and therefore should not be used in excessive proportions.

A primary advantage of the introduction of magnesium into explosive mixtures follows from the great amount of heat liberated in course of its combination with oxygen. Magnesium metal however particularly when very finely subdivided and when existing under the conditions obtaining in the explosive mixture, is somewhat lacking in stability and liable to slow oxidation. It has been found on the other hand that the magnesium-silicon alloys are sufficiently stable to permit of such use. In this respect the magnesium-silicon alloys are sharply differentiated from such alloys as those of silicon with calcium. For example calcium silicide corresponding substantially to the formula CaSi is a fairly stable compound, but alloys of calcium and silicon containing a materially higher proportion of calcium than the above are comparatively unstable; consequently it has not proven practicable to increase the power of explosive mixtures

containing calcium and silicon by increasing the calcium content of the alloy component. This does not apply however to the magnesium-silicon alloys, which possess a sufficient degree of stability for the purposes indicated even when the magnesium content is decidedly higher than corresponds to the known silicide MgSi. Such compounds, irrespective of the presence or absence of iron or other components, may be defined as alloys in which the magnesium is in excess of the equimolecular proportion to the silicon.

A further advantage in the use of magnesium-silicon alloys arises as follows:— The magnesium component of the alloy requires for its oxidation only about one-half of the oxygen required by the silicon component. It follows from this that the higher the relative proportion of magnesium in the alloy, the larger the permissible proportion of the alloy in the explosive mixture. It is therefore of great advantage in this connection that the magnesium-silicon alloys containing more than the equimolecular proportion of magnesium possess sufficient stability for use in explosive compositions.

Other advantages arising from the use of magnesium-silicon alloys in compositions of the kind above indicated follow from the relative lightness of these alloys and from the fact that the alloys are relatively brittle as compared with metallic magnesium, and are hence more easily pulverized to the requisite degree of fineness.

It will of course be understood that it is within our invention to use silicon in other reduced forms, for example as ferro-silicon, in conjunction with or in part replacement of the magnesium-silicon alloys. For example our invention contemplates the complete or partial replacement of ferro-silicon by magnesium-silicon alloys in such formulae as are disclosed in the copending application of John R. Mardick, Serial No. 207,389, filed December 15, 1917. Nor is our invention restricted to the use of magnesium-silicon alloys in which the magnesium

exists in higher proportions to the silicon than the equimolecular proportion; although we prefer in all cases to use alloys containing such higher proportions of magnesium.

We claim:—

1. A commercial explosive containing a nitro-aromatic body, an oxidizer, and a magnesium-silicon alloy. 55

2. A commercial explosive containing a nitro-aromatic body, an oxidizer, and a magnesium-silicon alloy in which the magnesium is in excess of the equimolecular proportion to the silicon. 60

3. A commercial explosive containing a nitro-aromatic body having at least three nitro-groups, an oxidizer, and a magnesium-silicon alloy. 65

4. A commercial explosive containing a nitro-aromatic body having at least three nitro-groups, an oxidizer, and a magnesium-silicon alloy in which the magnesium is in excess of the equimolecular proportion to the silicon. 70

5. A commercial explosive containing a nitro-aromatic body having at least three nitro-groups, an oxidizer, a plasticizing ingredient, and a magnesium-silicon alloy. 75

6. A commercial explosive containing a nitro-aromatic body having at least three nitro-groups, an oxidizer, a plasticizing ingredient, and a magnesium-silicon alloy in which the magnesium is in excess of the equimolecular proportion to the silicon. 80

7. A commercial explosive containing a nitro-aromatic body having at least three nitro-groups, an oxidizer, a plasticizing nitro-body, and a magnesium-silicon alloy. 85

8. A commercial explosive containing a nitro-aromatic body having at least three nitro-groups, an oxidizer, a plasticizing nitro-body, and a magnesium-silicon alloy in which the magnesium is in excess of the equimolecular proportion to the silicon. 90

In testimony whereof, we affix our signatures.

JOHN R. MARDICK,
FREDERICK MARK BECKET.
